Richard W. Sweet.

BY *Harry Schwedler*
ATTORNEY.

UNITED STATES PATENT OFFICE.

RICHARD W. SWEET, OF OAKLAND, CALIFORNIA.

CIGAR CUTTER.

Application filed September 11, 1922. Serial No. 587,360.

To all whom it may concern:

Be it known that I, RICHARD W. SWEET, a citizen of the United States, residing at Oakland, in the county of Alameda and State of California, have invented certain new and useful Improvements in Cigar Cutters, of which the following is a specification.

My invention is an improved cigar perforator.

The present method of effecting an air passage through a cigar is to cut off a small piece at the end, which usually results in the unwrapping of some of the leaves, which is very unsightly and makes the cigar smoke poorly.

In my perforator a plurality of pointed prongs are forced into the end of the cigar which provide an air passage with no mutilation of the end.

Another object of my invention is to provide a perforator which is simple in construction and inexpensive to manufacture.

Referring to the drawing which forms a part of this specification:

Figure 1 is a side view of my improved cigar perforator.

Figure 2 is a transverse sectional view taken on the line 2--2 of Figure 1.

Figure 3 is a side view of the plunger and prongs.

Referring more particularly to the drawing, the numeral 1 indicates a cigar perforator body which comprises a barrel 2 and a plunger 3 adapted to reciprocate in said barrel. The barrel 2 has a flared mouth 4 into which fits the cigar end.

The plunger 3 has a collar 5 formed near the upper end thereof and a second collar 6 at the bottom. Pointed prongs 7 are secured in the plunger 3 and project upwardly therefrom. A shoulder 8 is formed at the base of the mouth 4 and a second stop shoulder 9 is formed at the bottom of the

barrel 2. The collar 5 is adapted to rest against the stop 9 which prevents the plunger 3 from being withdrawn from the barrel 2. A coil spring 10 is positioned within the barrel 2 between the shoulder 8 and the collar 5.

The method of operation is as follows:

The cigar end is placed in the mouth 4. The plunger 3 is advanced within the barrel 2 until the collar 6 strikes the end thereof. This movement carries the prongs 7 into the mouth 4 and consequently into the cigar and perforates the end thereof. The plunger 3 is then released and the spring 10 retracts the plunger 3 until the collar 5 strikes the stop 9.

Having described my invention, I claim:

1. A cigar perforator comprising a barrel, a mouth formed on said barrel, a plunger within said barrel, a plurality of prongs secured to said plunger, a collar formed on said plunger near the upper end thereof, a second collar at the lower end of said plunger, a stop shoulder at the bottom of said barrel for engaging said collars, a shoulder at the base of said mouth, and a spring positioned between the first mentioned collar and said latter shoulder.

2. A cigar perforator comprising a one-piece barrel having a diverging mouth formed on one end thereof, a shoulder at the base of said mouth and a second shoulder at the other end of said barrel, a one-piece plunger slidable in said barrel having prongs extending from the upper end thereof, a collar near the upper end of the plunger and a second collar at the bottom of the plunger, said first mentioned collar being slid able in said barrel and a spring between said first-mentioned shoulder and said first-mentioned collar.

In testimony whereof I affix my signature.

RICHARD W. SWEET.
